BOTTLE CAP REMOVER

Leo M. Harvey, Los Angeles, Calif.

Application April 6, 1934, Serial No. 719,353

7 Claims. (Cl. 65—46)

This invention relates to a bottle cap remover which may be removably snapped on the neck of the bottle when not in use.

One of the principal objects of this invention is to provide an inexpensive bottle cap remover which may be removably mounted upon the bottle having the usual form of cap stopper, and so mounted that the device may be readily removed from the bottle when it is desired to lift the cap and after this operation either replaced upon the bottle or thrown away. In this way, the device is similar to the usual key furnished with each can of sardines, or other similar key-opened products.

15 A further object is to form the device of a single piece of wire for cheapness of manufacture, simplicity and ease of application to the bottle.

20 A further purpose of the invention is to so form the device that it will closely hug the bottle, whereby it will not be in the way when packing the bottles in cases or in handling.

25 A further object is to provide the bottle gripping portions with sufficient resiliency to permit the device to be sprung into position and to thereby yieldingly clamp on the bottle.

30 A further object is to make a modified form of the device of pressed metal having bottle gripping portions whereby the opener may be snapped on the bottle.

35 A further object is to so shape the holding elements of the opener as to cause the device to snugly hug the bottle for its full length and to thus act to resist any tendency which the device may have to rock or swing outwardly from the bottle.

40 Other objects and advantages of the invention will be apparent as the nature of the same is more fully understood from the following description and accompanying drawings, wherein is set forth what is now considered to be a preferred embodiment. It should be understood, however, that this particular embodiment of the invention is chosen principally for the purpose of exemplification, and that variations therefrom in details of construction or arrangement of parts may accordingly be effected and yet remain within the spirit and scope of the invention as the same is set forth in the appended claims.

45 In the drawings:

Figure 1 illustrates the device of this invention removably mounted onto the bottle;

Figure 2 illustrates a side view of Fig. 1;

Figure 3 illustrates the device in the act of lifting the bottle cap;

Figure 4 illustrates a second method by which the cap may be lifted;

Figure 5 illustrates a modified form of the opener removably mounted on a bottle;

Figure 6 illustrates a side view of Fig. 5;

Figure 7 illustrates this form of the invention in the act of lifting the bottle cap;

Figure 8 illustrates a further modified form of the opener; and

Figure 9 illustrates a side view of Fig. 8.

In the preferred form of the invention, as illustrated in the drawings, the bottle 10 may be of any of the common, well known types now in use, which are sealed by the usual form of crown cap 11. One draw-back to this form of bottle and cap has been the difficulty of removing the cap unless the proper form of opener is handy, which in many cases it is not. To remove this objectional feature, the opener of this invention is adapted to be removably snapped on each bottle during its

20 progress through the bottle-filling works, or even at the glass works where the bottles are made, so that removably mounted on each bottle will be a key or opening device for removing the cap. In order to render this feature practical, the devices

25 must be very inexpensive of manufacture and easily applied, and likewise easily removed from the bottle when required for lifting the bottle cap and may be thrown away with the cap.

The cap lifting device 12 of this invention is 30 preferably formed from a single piece of wire looped, as at 13, to form a head of such size as to partially straddle the cap 11. In this loop are swaged or otherwise formed a forward spur 14 and two rearward spurs 15. Extending from the

35 looped head 13 the wires form a handle 16, the ends 17 and 18 of which are bent or formed into curved portions which straddle and grip on the bottle, as shown in Figures 1 and 2. It will be

understood that the resiliency of the wire will 40 be sufficient to permit the curved end portions 17 and 18 to spread while being forced into place, whereby as soon as the ends pass the center of

45 the curvature of the bottle, the opener will snap into position and thus remain until later removed for use.

The easiest way to remove the device from the bottle is to, by means of head 13, swing this end of the opener outward, thus causing the device to 50 pivot on the neck at the junction points between the handle section 16 and the curved portions 17 and 18 until the ends of portions 17 and 18 will have been swung over the center of the rounded neck, whereupon the opener will freely leave the

bottle. The cap 11 may now be lifted in either of two ways, as shown in Figs. 3 and 4.

By giving the curved portions 17 and 18 a downwardly directed inclination, they endeavor to swing in a counter-clockwise direction, as viewed in Fig. 2, and thereby to snugly hold the head end of the opener against the bottle, and in this way they act to resist vertical rocking of the device while attached to the bottle. As may be observed from Figs. 1 and 2, the head 13 is not left in a flat plane, but is curved to closely fit the contour of the bottle, and as all other portions of the device likewise closely hug the bottle, there are no portions which protrude to interfere with packing or handling of the bottles.

The opener may be used as shown in Fig. 3, wherein the spur 14 is placed under the forward edge of the cap, the handle 16 projecting upwardly while the curved end portions 17 and 18 are directed downwardly. The heel of the head fulcrums upon the cap as the handle is pressed downwardly to effect the lifting of the cap.

In Fig. 4 the spurs 15 are positioned under the rear edge of the cap, and in this case as the handle is to be lifted it extends downwardly while the end portions 17 and 18 point upwardly and the front end of head 13 fulcrums on the cap. By lifting the handle, the cap will be lifted from the bottle.

It will be appreciated that the opener may be differently shaped and yet retain the feature of being able to be snapped on the bottle.

In Figures 5, 6 and 7 there is illustrated one example of a differently shaped opener which may be likewise snapped on the bottle.

This form of the invention is illustrated as being formed of a single piece of wire, but it is to be understood that it may be formed of several pieces of wire welded or otherwise fastened together.

This form of the opener includes a handle portion 20 shaped to closely follow the contour of the bottle. The handle portion 20 may be of more or less loop shape, and from the upper ends of which the curved spring arms 21 and 22 extend to a point a little beyond the center of curvature of the bottle to enable the opener to clamp thereto. In this form of the opener, the cap lifting means are formed upon the arms 21 and 22 and include the upwardly extending portions 23 and 24, each of which terminates in an inwardly projecting portion indicated at 25 and 26.

When it is desired to lift the crown cap the opener may be easily removed from the bottle and applied to the rim of the cap, as shown in Fig. 7. In this figure it will be noted that the projecting portions 25 and 26 are hooked under the rim of the cap, the portions 23 and 24 extending for a distance above its edge so that the arms 21 and 22 lie directly above the cap while the handle portion extends upwardly. Thus, by swinging the handle in a clockwise direction, as viewed in Fig. 7, the cap may be easily lifted from the bottle.

In some instances, it may be desirable to form the opener of a metal pressing, one form of which is illustrated in Figures 8 and 9.

In this form of the invention, the opener 30 may be provided with cap lifting means 31, which in this instance is in the form of a jaw. To mount the opener on the bottle, it may be provided adjacent its upper end with gripping arms 32 and 33, which are shaped and are of such length as to nicely fit around the bottle until the

ends thereof extend a short distance past the center of the neck curvature. The entire opener may be shaped to closely fit the contour of the bottle so as not to be in the way when the bottle is being handled.

The opener may be easily removed from the bottle and used in the ordinary way for lifting the cap, as will be readily understood.

Having shown and described my invention, it is to be understood that various changes and modifications may be made therein without departing from the spirit of the invention or the scope of the following claims.

I claim:

1. In a bottle cap removing device formed of a single piece of wire, a loop-shaped head engageable with a bottle cap for removing the same, a handle so formed that the ends thereof will yieldingly straddle and grip the bottle neck for attachment thereto when not in use, and the device being formed to closely fit the contour of the bottle neck when attached thereto.

2. In a bottle cap removing device, a loop-shaped head having a spur for engagement with the rim of a bottle cap, and a handle arranged to yieldingly straddle and grip the bottle neck for attachment thereto when not in use, and the device being formed to closely fit the contour of the bottle neck when attached thereto.

3. In a bottle cap removing device formed of a single piece of wire, a handle, and portions of the wire formed in angular relation to the length of the handle and curved for yieldingly gripping on the neck of a bottle for attachment thereto when not in use, and a cap lifting means formed at the other end of the handle and operable after the device has been removed from the bottle for removing the cap.

4. A bottle cap removing device formed of a single piece of metal, having means for yieldingly gripping onto the neck portion of a bottle for attachment thereto and a portion adapted to lie closely adjacent to and longitudinally of the bottle neck when not in use, and a cap engaging means formed on said device operable when the device is removed from the bottle for lifting the cap, all portions of said device being located below the cap when attached to the bottle neck.

5. A bottle cap removing device formed of a single piece of metal, having means for yieldingly gripping onto the neck portion of a bottle for attachment thereto and a portion adapted to lie closely adjacent to and longitudinally of the bottle neck when not in use, and a cap engaging means formed on said device, operable when the device is removed from the bottle for lifting the cap, all portions of said device being located below the cap and formed to closely fit the contour of the bottle when attached to the bottle neck.

6. A bottle cap removing device formed of a single piece of metal having means for yieldingly gripping onto the neck portion of a bottle for attachment thereto and a portion adapted to lie closely adjacent to and longitudinally of the bottle neck when not in use, and a cap engaging means formed on said device, operable when the device is removed from the bottle for lifting the cap, all portions of said device being located below the cap when attached to the bottle neck, said gripping means being arranged to extend beyond the center of curvature of the bottle to resist disengagement therefrom.

7. A bottle cap removing device formed of a single piece of metal, having means for yieldingly gripping onto the neck portion of a bottle, said

gripping means being arranged to extend beyond the center of curvature of the bottle to resist disengagement therefrom and being formed to grip the bottle neck intermediate the extremities of the device for attachment thereto, and a portion adapted to lie closely adjacent to and longitudinally of the bottle neck when not in use, and

a cap engaging means formed on said device, operable when the device is removed from the bottle for lifting the cap, all portions of said device being located below the cap when attached to the bottle.

LEO M. HARVEY.
